UNITED STATES PATENT OFFICE

NEIL P. LARSEN, OF CLEVELAND, OHIO, ASSIGNOR TO THE AMERICAN COACH & BODY COMPANY, OF CLEVELAND, OHIO, A CORPORATION OF OHIO

CRANE

Application filed September 18, 1930. Serial No. 482,733.

This invention relates to erecting booms of a type adapted for use in connection with motor vehicles particularly those used by utilities companies in the erection of poles 5 and the like.

An object of the present invention is to provide a boom adapted to be removably attached to the front end of the chassis of a motor vehicle so that the work of erecting 10 poles and like devices, may be observed by the driver while sitting in a normal position within the cab of the motor vehicle.

A further object of the present invention is to provide means for directly receiving 15 the load suspended from the boom and thus avoid subjecting the springs of the motor vehicle to the load.

With the objects above indicated and other objects hereinafter explained in view, the 20 invention consists in the construction and combination of elements hereinafter described and claimed.

Referring to the drawing:

Figure 1 is perspective view of a motor 25 vehicle showing the location of the boom embodying the present invention and the method of attachment.

Fig. 2 is a front elevational view of the means for receiving the load suspended from 30 the boom.

Fig. 3 is a side elevational view of Fig. 2.

A standard type of motor vehicle 10 is illustrated in Fig. 1 and is characteristic of the 35 type of motor vehicle used by the utilities companies in their erection and repair work. The vehicle is provided with the usual chassis 11 which has secured to the forward end thereof the boom which will be later described in more detail.

40 A pair of brackets 12 are spaced apart as shown in Figs. 1 and 2 and are bolted or otherwise secured at 13 to the forward ends of the chassis 11. These brackets 12 extend upwardly and are adapted at their upper ends 45 to receive a transversely extending rod 14 which may be welded or otherwise secured to the upper ends of the brackets 12. The opposite ends of the transverse rod 14 are provided with circumferentially extending 50 grooves 15 which have disposed therein the

hook ends 16 of the boom 17. It will be noted that these hook ends 16 are detachably connected with the opposite ends of the transverse rod 14 so that the boom may be disengaged from the front end of the motor vehicle 55 when not in use. The boom in the present instance consists of a pair of rods 18 which converge toward their upper ends and are pivotally connected at 19 to the upper end of a guy 20.

This guy 20 comprises telescopic portions 21 and 22 which may be secured in any desired position by a locking pin 23 which is adapted to pass through suitable aligned openings in both of the telescopic portions. 60 This guy 20 is made adjustable so as to position the boom 17 at the desired height and to maintain the same in the adjusted position.

The lower end of the guy 20 fits within a socket 24 which has its lower ends bifurcated at 25 and provided with aligned openings through which a rod 26 extends. Between the bifurcated ends 25 of the socket 24 and also encircling the rod 26 is a sheave 27 for a purpose to be later described. 70

The ends of the rod 26 are secured by welding or otherwise to the upper ends of a pair of brackets 28 which in turn are suitably bolted or otherwise secured to a portion of the motor vehicle adjacent the top 75 thereof as clearly shown in Fig. 1.

At the rear portion of the motor vehicle a rod 29 is secured at its ends to the motor vehicle and mounted for rotation upon the rod 29 is a sheave 30.

80 The guy 20 has secured thereto a sheave 31 adjacent its lower end while a sheave 32 is carried by the upper end of the guy 20 and adapted to rotate about the axis of the pin 19. A cable 33 has a hook 34 at one end thereof and extends over the sheave 32 under the sheave 31 over the sheave 30 and has its opposite end connected to the drum of a winch, not shown, which is usually carried upon the interior of the motor vehicle for the purpose of raising and lowering the load 85 which is suspended upon the hook 34.

90 The boom 17 being supported upon the forward end of the chassis 11 would necessarily, in operation, subject the springs of 95

the motor vehicle to excessive strain and it is, therefore, advisable to provide a means for receiving the load and thus relieving the springs of any possibility of injury on this account. However, in providing such means it is essential that the motor vehicle shall still remain in operative condition so as to be moved from one pole, which has been erected, to the next pole which is to be erected, during which time the load may be suspended from the boom.

10 A pair of tubular members 35 are positioned vertically and are welded or otherwise secured to the forward portions of the 15 brackets 12. These tubular members 35 extend forwardly beyond the forward end of the chassis 11 and slidably receive therein members 36. These members 36 are vertically adjustable, or longitudinally adjustable 20 within the tubular members 35, and are provided with aligned openings within which are disposed pins 37 for maintaining these members 36 in the desired adjusted positions. The lower ends of the members 25 36 have bifurcated ends 38 to receive therebetween rollers or wheels 39 which are rotatably mounted upon transversely extending pins 40 carried by the bifurcated ends 38.

It will therefore be seen that when in operation 30 the members 36 are lowered until the rollers 39 engage the ground ahead of the motor vehicle and the pins 37 inserted through the aligned openings in the members 36 and the tubular members 35 to hold these members in proper position. In view 35 of the fact that the tubular members 35 are directly connected within brackets 12 which support the boom 17 the load is therefore supported directly upon the ground and 40 through the rollers 39, thus eliminating any unnecessary force being carried by the springs of the motor vehicle.

The motor vehicle may be operated and may travel over a given distance during the 45 erection of poles or the like while the rollers 39 are in engagement with the ground, thus providing a support for the boom which will not interfere with the manipulation of the motor vehicle. A further advantage 50 in the arrangement is that the operator may see the erection operations and at the same time move the motor vehicle so as to transport the pole or other article to the proper destination.

55 When the boom is not in use it may be disconnected from the transverse rod 14 and the guy 20 disengaged from the socket 24 and in collapsed condition may be carried by the supports 40 along the side of the motor vehicle. At the same time the members 60 36 may be elevated so as to raise the rollers 39 out of engagement with the ground and held in elevated position by means of the pins 37 to thus not interfere in any manner 65 with the operation of the motor vehicle.

While I have described the preferred embodiments of the invention it is to be understood that I am not to be limited thereto, as changes and modifications may be resorted to without departing from the spirit of the 70 invention as defined in the appended claims.

Having thus described my invention I claim:

1. In combination with a motor vehicle having a chassis, said chassis including a 75 frame having a pair of side rails, a crane mounted on the forward end of said chassis, said crane including a pair of upstanding bracket members secured to the side rails adjacent the forward ends thereof, one of said bracket members being secured to each of said frame side rails, a transverse member secured to said bracket members, a boom including a pair of rods having their lower ends detachably secured to said transverse member adjacent the 80 ends thereof, said rods converging at their upper ends, a guy member having its upper end pivotally secured to the upper ends of said rods, the lower end of said guy member being secured to the vehicle adjacent the 85 mid-portion thereof, and vertically adjustable ground engaging means associated with said bracket members, said means being adapted to support a portion of the weight of the 90 crane and the load carried by it.

2. In combination with a motor vehicle having a chassis, said chassis including a frame having a pair of side rails, a crane mounted on the forward end of said chassis, said crane including a pair of upstanding bracket members secured to the side rails adjacent the forward ends thereof, one of said bracket members being secured to each of said frame side rails, a transverse member secured to said bracket members, a pair of rods having their lower ends detachably secured to said transverse member adjacent the ends thereof, said rods converging at their upper ends, a guy member having its upper end pivotally secured to the upper ends of said rods, the lower end of said guy member being secured to the vehicle adjacent the mid-portion thereof, said guy member being variable in length, and vertically adjustable ground 100 engaging means associated with said bracket members, said means being adapted to support a portion of the weight of the crane and the load carried by it.

3. In combination with a motor vehicle 105 having a chassis, said chassis including a frame having a pair of side rails, a crane mounted at the forward end thereof, said crane including a pair of bracket members secured to the forward ends of said side rails, a 110 transverse member secured to said bracket members, said transverse member being provided with grooves adjacent the ends thereof, and a boom constructed of a pair of rods, said rods being slotted adjacent their lower ends,

said slots being adapted to receive the grooved portions of the transverse member.

4. In combination with a motor vehicle having a chassis, said chassis including a frame having a pair of side rails, a crane mounted at the forward end thereof, said crane including a pair of bracket members secured to the forward ends of said side members, a transverse member secured to said bracket members, said transverse member having a circumferential groove adjacent each end, and a boom constructed of a pair of rods, said rods being slotted adjacent their lower ends, said slots being adapted to receive the grooved portions of the transverse member.

5. In combination with a motor vehicle having a chassis, said chassis including a frame having a pair of side rails, a crane mounted at the forward end thereof, said crane including a pair of bracket members secured to the forward ends of the side members, a transverse member secured to said bracket members, said transverse member having a circumferential groove adjacent each end thereof, and a boom constructed of a pair of rods, said rods having slots adjacent their lower ends, said slots being adapted to receive the grooved portions of the transverse member, the open ends of said slots being toward the forward end of the vehicle.

In testimony whereof, I hereunto affix my signature.

NEIL P. LARSEN.
